UNITED STATES PATENT OFFICE.

AUGUSTE A. GOUBERT, OF JERSEY CITY, NEW JERSEY.

CENTRIFUGAL MACHINE.

SPECIFICATION forming part of Letters Patent No. 280,465, dated July 3, 1883.

Application filed August 17, 1882. (No model.)

To all whom it may concern:

Be it known that I, AUGUSTE A. GOUBERT, of Jersey City, Hudson county, in the State of New Jersey, have invented certain new and useful Improvements relating to Centrifugal Sugar-Machines, of which the following is a specification.

Centrifugal machines have been long used, and are much appreciated in rapidly and effectively expelling the fluid and semi-fluid material from between the crystals of sugar. The undrained sugar is deposited in a circular vessel, termed a "basket," having wire-gauze or finely-perforated metal for the sides, and the vessel is whirled so rapidly that the centrifugal force expels the sirup and leaves the crystals dry.

I have devised important improvements in the construction and operation. The considerable power required is applied on a pulley extending down from the basket. The brake is applied to a conical surface interposed between the belt and the basket. It is applied on a ring which is capable of turning around on the pulley, and is provided with wings which fit closely under apertures in the bottom of the basket and constitute a partially-rotating valve which controls the discharge of the dry sugar. This valve is operated by simply giving a partial rotation to the basket when the brake has arrested its motion by the strong friction induced on the valve. An upright sleeve which incloses the rapidly-revolving shaft is centered by springs mounted at a distance and connected by rods, and a universal joint for such sleeve is mounted between these spring-connections and the basket. The framing supporting the machine is constructed in the shape of a cylinder, allowing the sugar to be discharged downward in the interior thereof. At the same time this framing serves as an abutment for the springs which control the position of the sleeve which incloses the shaft or spindle.

The accompanying drawings form a part of this specification, and represent what I consider the best means of carrying out the invention.

Figure 1 is a central vertical section. Fig. 2 is a section on a horizontal line just below the basket in Fig. 1. Fig. 3 represents the valve detached. Fig. 4 is an elevation, partly in

section, at right angles to Fig. 1, showing the middle portion of the apparatus.

Similar letters of reference indicate corresponding parts in all the figures. 55

All the fixed framing is marked A, certain portions being designated by further marks, as A' A², when necessary.

A' is a fixed casing adapted to catch the sirup and lead it away through a suitable channel. 60 (Not represented.)

B is the basket and shaft to which it is rigidly connected, some portions being designated, when necessary, by additional marks, as B' B².

B' is a stout central boss or hub, and B² a 65 shaft extending down therefrom. A small concentric extension downward from the basket constitutes a pulley, B³, to receive a rapidly-running belt, of proper width, leading from a steam-engine or other power. (Not represented.) 70 This pulley B³ is hollow and allows the necessary play of the shaft therein.

C is a ring free to revolve on the upper portion of the pulley B³, and equipped with three broad horizontal radial extensions or wings, 75 C' C' C', which serve as valves to open and close three corresponding apertures, b b b, in the rigid bottom of the basket. One or more stop-pins, B⁴, connecting this valve with the basket through properly-curved slots c, allow 80 the proper amount of turning motion of the valve to open the passages b and close them, as required.

D is the forked brake-lever. It turns on a center, d. It is adapted to arrest the rotation 85 of the basket by friction induced through friction-pieces D², pressing against a conical surface on the under face of the valve-ring C.

A² is a portion of the fixed frame-work partially surrounding the pulley B³, and forming 90 a support for the center d of the lever D. It also, by the aid of extensions A³, shields the belt J against any possible contact of the sugar, which is discharged downward from the basket, as will be described farther on. 95

G is a sleeve, of cast-iron or other suitable material, inclosing the shaft B². It has a long babbitt bearing, G², near its upper end. An exterior shell, G', surrounding the sleeve G, and cast in one therewith, is finished on the 100 exterior to form a sufficiently broad zone of a spherical bearing. This matches in a corre-

sponding spherical seat in the interior of the fixed framing A^2 . This bearing allows the sleeve, and consequently the inclosed shaft and its connections, to rock or oscillate on the 5 sphere or partial sphere G' as a center.

The basket B , with its load of sugar, is rarely, if ever, exactly centered. The center of gravity, which is a little out of line of the center of the shaft B^2 , tends to remain stationary and to 10 cause the axis of the shaft to describe a small circle. It tends to revolve around the center of gravity of the basket and its load. The sugar is deposited carelessly. If the center of gravity of the mass is one-eighth ($\frac{1}{8}$) inch from 15 the axis of the shaft B^2 , the latter will, when the basket is revolved at the high velocity required, tend to describe a circle of one-eighth ($\frac{1}{8}$) inch radius.

The spherical bearing G' , at the same level 20 as the firm bearing G^2 for the inclosed shaft, holds the latter rigidly to its place at that point; but its spherical form allows the upper end carrying the basket B to gyrate, inducing a counterpart of the same gyration in that 25 portion of the shaft B^2 , and consequently of the inclosing sleeve G , which is below the spherical bearing. I allow such motion; but by confining the lower end, through the aid of springs, I control the extent of the oscillating motion of the sleeve, and consequently 30 the extent of the gyrations of the basket. I restrain the motion of the lower end by tie-rods extending radially outward, and strained by springs of rubber or other suitable material 35 mounted in positions convenient of access at or near the exterior of the frame-work. The rods are marked H and the springs I . The inner ends of the rods engage with eyes G^3 , cast or otherwise firmly fixed on the sleeve. 40 The outer ends extend through the cylindrical part A^3 of the frame-work, which latter supports the lower cylindrical portion, A^4 , of the stationary part A' . The outer ends of the rods H are threaded, and carry nuts H' and jam-nuts H^2 , which press on the springs through 45 the intervention of plates I' . This allows the tension of the springs to be adjusted so that the lower end of the sleeve G , and consequently the inclosed shaft B^2 , and the basket, with its 50 contents, may be restrained in their gyratory motion to such extent as is found most expedient. Sugar distributes itself in a basket under the violent centrifugal force to which it is subjected, so that the distance of the center 55 of gravity from the axis of the shaft B^2 is slight. It is important to be able to graduate the force of the springs to allow the gyratory motion to be performed with just sufficient restraint. The sugar is introduced through the top of the basket 60 in the ordinary way. The motion communicated by the belt J on the pulley B^3 whirls the sugar until it is spread forcibly within the basket and drained, the entire revolving parts (as also the sleeve G , which supports the same) 65 rocking or oscillating on the center (marked $*$) of the spherical bearing G' , and inducing a coun-

terpart of the gyration at the lower end of the sleeve G , which is allowed, and also restrained by the springs I , connected by the rods H , adjusted by the nuts H' , and secured by the jam-nuts H^2 . When the sugar is sufficiently drained, the attendant stops the transmission of power through the belt J by shifting it onto a loose pulley on the driving-shaft, (not represented,) or by any other suitable means, and applies 70 friction through the lever D , turning it on the center d , and lifting on the ring D' , carrying the wooden blocks D^2 , which induce the required strong friction against the conical under surface of the valve-ring C . The ring D' 75 is provided with two trunnions, d' , which stand in vertical slots in the framing A^2 , and, extending out through the same, are engaged by the forked brake-lever D . The ring C is capable 80 of performing a partial revolution relatively to the basket, being limited in its motion by the pins B^4 , fitted in the slots c . The friction induced by the brake-blocks D^2 holds this partially-revolving ring C firmly at that extremity 85 of its motion which presents its wings C' under the holes b . This is the position which they 90 ordinarily hold when the machine is in use. So soon as the motion is completely arrested the attendant, leaving the brake-lever on, applies the force of his hands directly or indirectly to 95 the basket and gives it a partial rotation backward, or in the direction opposite to that in which it has been revolved. This, by the partial rotation of the basket relatively to the valve, opens all the apertures b . The sugar 100 lying against the interior of the basket is now loosened in the ordinary manner, and is rapidly discharged through the openings b , falling without appreciable obstruction within the parts $A^4 A^5$ of the framing, past the rods H , 105 near the bottom, and also past the belt J , near the top, the belt being shielded by being extended through narrow covered passages A^3 , which may be produced by extending the central casting, A^2 , outward in the proper form, or may be made by sheet-metal attachments held in place by any suitable means. So soon as the sugar is discharged a partial 110 revolution of the basket B forward closes the apertures b by the wings C' , when the 115 brake-lever D may be tilted to liberate the valve, another charge of undrained sugar introduced, and the belt J allowed to again rapidly whirl the basket and its contents. The considerable chamber g' within the spheroidal 120 bearing G' , and the extension of the sleeve upward therefrom and exterior to the babbitted bearing G^2 , serves as a capacious oil-cup. One or more openings therefrom through the babbitt bearing G^2 allow the oil free access 125 to one or more vertical grooves on the interior of the bearing, and thus completely fill the limited space within the sleeve G with oil. The shaft B^2 revolves in a bath of oil. Ordinary provisions (not represented) allow the 130 oil to be drawn out at intervals and fresh supplied. I prefer filling the chamber g' loosely

with cotton waste or analogous material. The step at the lower end of the shaft is formed so as to afford a firm bearing laterally, not against any fixed object, but against the interior of the sleeve G, which is allowed to yield. The end-wise thrust, due to the weight of the revolving parts, is received on a series of loose disks, E, adjusted vertically by a screw, G⁴.

Modifications may be made in the forms and proportions of the details without departing from the principle or sacrificing the advantages of the invention. Parts of the invention may be used without the whole. The spheroidal bearing may be increased in diameter. The bearing-zone may be widened. There may be a greater or less number of the apertures b and wings C of the valve to close them. The valve-apertures b may extend out farther, the wings C being correspondingly extended, and the exterior curbing or framing, A⁴, below being similarly increased in diameter. The rim or periphery of the basket may project downward a little.

I do not claim applying the brake by a mere contact of the basket with a fixed ring, as by lowering the basket on a fixed brake-surface.

I claim as my invention—

1. In a centrifugal machine, the hollow pulley B³, fixed directly to the basket, and arranged to serve as and for the purposes herein specified.
2. In a centrifugal machine, the brake-lever D and brake-ring D' D², raised and lowered under the basket, in combination with a conical bearing-surface revolved with the latter, as herein specified.
3. In a centrifugal machine, the sleeve G,

embracing the shaft or spindle B², and provided with the spherical bearing G', carrying the weight of the revolving parts, in combination with the yielding or elastic bearing G⁴, arranged at or near the lower end of the sleeve, and adapted to serve substantially as herein specified.

4. In a centrifugal machine, the springs I, rods H, sleeve G, spherical bearing G', shaft B², and basket B, combined and arranged relatively to each other and to the frame A² and casing A' A⁴ A⁵, so as to allow the bottom of the spindle to oscillate to a limited extent, substantially as herein specified.

5. In a centrifugal machine, the sleeve G, having a capacious chamber, g', at the top, with one or more communicating passages, g, and with provisions for gyrating by the yielding springs I, so as to support the shaft B² in a bath of lubricating material, as herein specified.

6. In a centrifugal machine, the framing A⁴ A⁵, arranged to perform the several functions of supporting the revolving parts, affording an inclosed passage-way for the sugar, and forming a fixed abutment for the springs I, in combination with said springs, and with connections therefrom to a movable bearing for the shaft B², all substantially as herein specified.

In testimony whereof I have hereunto set my hand, this 9th day of August, 1882, in the presence of two subscribing witnesses.

AUGUSTE A. GOUBERT.
